PHILIP STANLEY SMITH, OF DENVER, COLORADO.

PAPER BOX.

1,149,412.

Specification of Letters Patent. Patented Aug. 10, 1915.

Application filed February 16, 1914. Serial No. 319,022.

To all whom it may concern:

Be it known that I, PHILIP S. SMITH, a citizen of the United States of America, residing in the city and county of Denver and State of Colorado, have invented a new and useful Paper Box, of which the following is a specification.

My invention relates to boxes, and especially relates to cigarette holding boxes; and the objects of my invention are: First, to provide a box of paper and paste-board, and of other suitable materials, which can be made in part portions, and then assembled in a complete box having a body portion and an opening cover portion. Second, to provide a box of paper or paste-board or other suitable material, which is first constructed in separate and independent parts or sections, said parts or sections being then assembled together by any suitable means by which a box is produced having a body and a cover portion, and the cover portion is hinged to the body portion. Third, to provide a box in which the base and body portions are made in equal size and half parts, and the body portion is made up into an independent part, and is secured in the base portion, and receives over it the cover portion, and in which these parts are covered with a finished paper or other material arranged to form a hinged member for the cover upon the base portion, and also a sealing strip that can be used to seal the cover to the base after the box has been filled with merchandise and is ready to be offered for sale.

I attain these various objects by the employment of any suitable box making machine or mechanism, or of any combination of box making machines, or of coöperating machine elements operatively arranged to make, gum and assemble the coöperating parts of a paper and paste-board box together into a complete covered box.

My method of making paper and paste-board boxes consists of first making separate and independent part portions or half part and other parts of the box by themselves and then in assembling these various parts or portions into a complete box, and preferably into a box having a cover portion that is hinged to a base portion of the box.

I have not, however, illustrated any box making machine or mechanism or any combination of box making machines for forming the separate and independent parts of

boxes made under my improved method, or for collecting, assembling and securing said separately made parts of the box into a complete box, as my improved method contemplates the use of any and every kind and type of box making machine or combination of box making machines that can be used for this purpose. I have, however, illustrated the different parts of a box constructed by my improved method, as they are separately and independently made, and also illustrated how they are assembled and secured together to form a complete box having a sealed cover and a hinged cover after the seal is broken.

In these accompanying illustrations: Fig. 1 is a plan view of a paste-board box blank, and forms one blank of a pair used in the making of a box by my method of box construction. Fig. 2, is a plan view of a similar paste-board box blank, and forms the other blank of the pair of blanks necessary in the making of a box by my method of box construction. Fig. 3, is an edge view of the blanks 1 and 2. Fig. 4, is a plan view of a finishing blank used to cover one of the paste-board blanks shown in Figs. 1 and 2. Fig. 5, is a plan view of a finishing blank similar to the blank shown in Fig. 4, and is adapted to cover the other paste-board blank of Figs. 1 and 2. Fig. 6, is a plan view of a finishing blank showing the blank provided with a straight or a curved or the tapering side flap. Fig. 7, is a perspective view of the side shaped body portion that forms the inside lining or body of the box. Fig. 8, is a plan view of a finishing blank showing a paste-board blank on top of it, the two blanks being in position in which both the finishing blank and the paste-board blank can be folded together and at the same time into a box member. Fig. 9, is a perspective view showing a paste-board blank and a finishing blank partially folded into a box member. Fig. 10, is a perspective view showing the paste-board blank and a finishing blank folded up into a box member at its ends and sides, and shows one side flap in position to be folded over into the interior of the box member and against its side, the dotted line 11^A representing where the end of the side flap would come when adhesively secured to the inside surface of the side of the box. Fig. 11, represents a perspective view of a base member of the box without its body portion.

Fig. 12, represents a perspective view of a completed cover member of the box. Fig. 13, is a perspective view of the completed base member of the box, showing the body portion of the box in position in the base. Fig. 14, is a perspective view of an assembled base and its cover into complete box. Fig. 15, is a perspective view of an assembled box with the cover adhesively secured to the base and consequently hinged to the base, and showing the cover slightly raised from the base and swung up on its hinge member. Fig. 16, is a perspective view of a modification of the arrangement and position of the side flaps, and Fig. 17, is a perspective view of a completed and assembled box embodying my invention.

Similar letters of reference refer to similar parts throughout the several views.

Referring to the drawings,—The numerals 1 and 2 designate two paste-board blanks. These two blanks are cut from a sheet of paste-board into forms that are adapted to be bent up and secured at the sides and ends into a base portion 1^A of a box, and a cover portion 2^A of a box, see Figs. 10, 11 and 12. These two paste-board blank portions 1 and 2, which are illustrated in Figs. 1 and 2, are preferably made just alike as to shape and size, and as illustrated they represent an oblong or parallelogram shaped square ended box having sides and end portions that are arranged at right angles to each other, and in which the sides 3 and 3^A, are longer than the ends 4 and 4^A. It will be understood, however, that square boxes can be made having sides of equal lengths, and also that cap or cover portions can be made of a different depth than the depth of the base, although these parts are preferably made of equal depths.

My present invention as preferably described, contemplates the making of square shaped boxes having sides that are longer than their ends, and contemplates the making of boxes of various sizes that have a ring shaped body portion 5, that sets inside of and is secured to the blank base portion 1^A. The cover portion 2^A of the box, also sets loosely over the ring shaped body portion 5, and is hinged to the base portion by a suitable covering material. These blank base and cover portions 1 and 2, are first cut out of sheets of paste-board into the blank forms shown in Figs. 1 and 2, and their corner portions 6 are cut away to leave the sides sides 3 3^A, and ends 4 4^A, entirely free and independent of each other, and at substantially right angles to each other, which operation can be performed in machines adapted to cut out the corners of box blanks. The paste-board blanks are then provided along their sides and ends with parallelly arranged grooves 7, which are arranged parallel with their sides and ends, and are ar-

ranged to meet each other at the junction of the corners of their sides and ends. The object of these grooves or creases is to permit the blank base and cover portions 1 and 2 to be broken along these grooves or creases, and the operation of forming these grooves is termed scoring, and is applied to the blanks after they are formed with their corners cut out by scoring machines, which are especially designed and adapted for this purpose, and the art of making paper boxes is well supplied with scoring machines that can be used for this purpose.

The paste-board blanks for forming the base and cover portions 1 and 2 of the cigarette box, are now properly formed and scored, and they are ready for the next step treatment of my improved method of construction. This next step treatment is to place or set these paste-board blanks onto a finishing covering blank especially designed to cover them in such a manner that the base and its cover when assembled into a completed box, will have a finished appearance, and will be artistically covered with some material having a neat finished surface, and that will act at the same time as a binding and covering material. Smooth calendered or other surface finished paper is almost exclusively used for this paste-board covering material, but certain fabrics like silk, leather, and other material may be used if desired, but as paper is universally used, I will confine the description of the covering material throughout the remainder of this specification to finishing paper, and the next step in my new method of box construction is to provide a finishing paper covering blank of such form that it can be used both as a binder for securing the corners of the adjacent grooved or scored sides and end portions of the paste-board box forming blanks together, as well as act as an artistic and finished surfaced covering material for the paste-board box forming blanks 1 and 2, that will render the base and cover portions of the box when combined into a complete box as shown in Fig. 17, more pleasing in appearance and of a smooth and finished appearance. I employ two, or a pair of these finishing paper blanks 8 and 8^A, see Figs. 4 and 5. These finishing paper blanks are of peculiar and novel form and are arranged to act as the finished covering material, and also as a hinge, to hinge the cover to the base, and also to act as a seal, to seal the cover to the base, as will be fully described hereinafter. They consequently form a very essential and important element of my invention. They may be made of any kind or character of finished and artistically printed and designed paper, or of any other suitable material. They are made with projecting side and end flaps, which project beyond their central body portions, which are made of a size

to cover the bottom of the base portion paste-board blank 1, and the top of the cover paste-board blank portion 2, and in Figs. 4, 4, and 5, I have shown them provided with 5 dotted score lines 8^a, in order to define the position of the outer boundaries of the body portion of the paste-board blanks, when laid on them, although when these finishing blanks are made up for actual use they are 10 not provided with these score lines. Consequently these dotted scoring lines 8^a show 15 the size of the body portion of these finishing blanks is the same as the size of the body portions of the paste-board box 16 forming blanks within their grooved scoring lines 7, and the scoring lines 8^a on the finishing paper blanks show that the paste-board blanks can be placed centrally and evenly 20 on top of the finishing paper blanks, so that 20 the body parts of a paste-board blank will register evenly over the finishing blank. Two of the ends of these finishing paper blanks are provided with projecting square ended flaps 9 and 9^a, which are separated at 25 their corners by a V-shaped cut 10, that is approximately straight along the inner edge 30 of the body portion of the blank cover, and 35 curves outwardly from the body to the 40 terminal ends 11 and 12 of the projecting flaps 45 9 and 9^a, or these cuts if desired can be 50 made straight, as shown in Fig. 6. The 55 opposite sides 13 and 13^a of the finishing paper blank, Fig. 4, and the sides 14 and 14^a of the 60 finishing blank, Fig. 5, are of unequal length 65 outside of the scoring lines 8^a. The ends 13 and 14 of the finishing paper blanks, Figs. 4 and 5, project, as illustrated, a short distance 70 beyond the terminal ends 11, of the flaps 9 and 9^a, and if desired they may be made of less 75 or greater length than as illustrated, as the 80 proportionate length of these flaps can be 85 varied as desired, to fit smaller or larger 90 boxes than cigarette holding boxes. The 95 opposite side flaps 13^a and 14^a of the finishing 100 paper blank, Figs. 4 and 5, are made to extend further from the scoring lines 8^a of 105 boxes shown 4 and 5, which are placed on the 110 drawing to define the outside boundaries of 115 the body portion of the finishing blanks, 120 than the side flaps 13 and 14, and they are 125 consequently longer than the flaps 13 and 14, and this makes the side flaps of each of these 130 finishing paper blanks of unequal length.

The object of making the side flaps of these blanks of uneven lengths, is to enable the largest flaps to be used as a hinge on one side of the finished base and cover when assembled together, and as a sealing strip on the opposite side of the base and cover from the hinge when assembled together. Consequently these covering blanks are made in pairs and the two pieces or halves of a pair of these covering blanks are alike, and they are so formed and arranged that they will wrap around the base and cover

of the box in such a manner that the elongated side flap of one blank acts as a hinge between the cover and the base on one of their adjacent sides, and the elongated side flap of the other blank acts as the sealing 70 strip that seals the cover to the base and the base and cover together on their opposite sides form their hinge flap, after the box has been filled with cigarettes or any other commodity. 75

There is another essential element in the members of the boxes constructed by my improved method, which forms an essential feature of it, and this element comprises a body portion 5. This body portion 5 is a 80 square frame made of a strip of ribbon paste-board, and made to fit snugly within both the cover and base portions of the box, and it is adapted to be secured within the base. This strip of ribbon paste-board is 85 first covered with a finished surface paper that is creased or grooved at three of its corners. This strip of paper covered paste-board is then bent into a square frame, and its free ends 15 and 16 are brought together 90 and are secured together by an extending end 17 of the finished covering blank, which is lapped from one free end around the other free end, or these corners may be secured together by gummed strips in a corner securing machine as is practised in the art 95 of making all kinds of paper boxes.

These body portions of the boxes constructed by my improved method of making boxes, are consequently wholly made and 100 prepared on machines used at present in the art of making paper boxes. I do not illustrate these machines, as they do not form an element of my method of constructing cigarette holding and other boxes, which can 105 be done if desired by hand.

I have now described the two equal half parts or portions of paste-board box forming blanks that form the base and cover portions of boxes constructed by my method, 110 and also the pair of finished paper blanks that are used as a finished and artistic covering for the paste-board box forming blanks, and which act to hinge the cover and base together, and also to seal them together 115 after the box has been completed, and filled with cigarettes, or with any other commodity that is to be offered for sale, and have described the ring shaped body portion of 120 the boxes, and have stated that all of these 125 parts can be made on box making machines at present in use.

My improved method, however, of constructing and making cigarette holding and other boxes, contemplates the various parts 125 of my boxes as described as essential elements of my invention, as to their forms, and as to the arrangement of those features that co-operatively unite with each other in the assembling of them into a completed 130

hinged and sealed box; and while these special half parts and portion member of boxes constructed by my improved method can be made on machines at present in use, the particular machine that I shall employ for making them will be made the subject of a separate application for a patent.

I will now describe the method I employ for assembling the parts.

- 10 As some manufacturers of cigarettes like to insert labels containing descriptive and advertising printed matter in the inner top wall of the cover or on the floor of the base, or in both of these parts of the box, labels
15 can be pasted in both of these members, or only in the cover, as desired, by suitable machine mechanism that is well known in the art. The finishing paper blanks are first
20 gummed on one side only, and they may be either wholly or partially gummed, as desired. A quantity of the finishing paper blanks is then placed in a convenient position to be fed into a position and place
25 where the paste-board box forming blanks can be placed centrally on top of them, and so that the grooved and scored lines of these paste-board forming blanks will register centrally over the body of and even with and over the corners of the cuts
30 at the ends of the flaps of the finishing blanks, as shown in Fig. 8. The paste-board box forming blanks are then subjected to pressure and action that is adapted to break
35 their marginal side and end flap portions along their grooved or scored lines, without however separating the fiber of the paste-board, after which they are ready to be bent to stand at right angles to the body portions of these blanks, into walls that
40 will stand vertically to the floor and top portions of the base and cover, when they are properly secured together at their ends, and that stand at right angles to each other at their corners, and at this point I wish to
45 state that those unsecured corners can be secured together independently of my finished paper blanks by stay strips applied by the commonly used machinery, or they can be secured together by my finished paper blank without the use of independent stay strips, or they can be secured together by both.

I preferably, however, use my finished paper blanks for the purpose of securing the erected sides and ends of the paste-board base and cover blanks together at their corners, and so form and arrange and apply these blanks that the corners are strongly and artistically secured together in vertically correct and square relation to each other and to the floor and top of the base and cover. Then when the base and cap portions of the box are moved onto the finished paper blanks, a suitable pressure is brought against the inside of the base

against its floor, which glues the bottom of the paste-board blank of the base portion of the box to the gummed surface of the finished paper blank, which is underneath it. This operation is also performed with paste-board blanks of the cover portion of the box. Additional means is then brought into action, which operates to fold the opposite ends 9 and 9^A of the finished paper blank, and also the ends 4 and 4^A of the paste-board base and cover blanks together, up into the opposite end walls of the box, as follows: The end portions 9 and 4 are folded, pressed, and glued together to form one end wall of the cover and base portion of the box, and the end portions 9^A and 4^A are folded, pressed, and glued together to form the opposite end-wall of the base and cover portions of the box. The base and cap portions being just alike, any two of these parts of the box can be picked up after they are formed, and one part will be the base and the other part the cover. There is no difference in the construction and size of these members until after the ring shaped body portion 5 has been inserted in one of them, except that if one of these parts should have a printed label glued in its top, this member would then become permanently the cover of the box, while those parts in which the ring-shaped body portion is inserted, become the base portion of the box. In making these parts by machinery, they would be made up first just alike in successive order, but almost instantly afterward each alternate part would receive a label, and would become the cover, while the intermediate part would receive a ring shaped body portion and would become the base member, and these base and cover portions would then be assembled into completed hinged boxes. The ends 11 and 12 of the finished paper blanks are made enough longer than the width of the paste-board blanks to project beyond them, and these overlapping ends 11 and 12 are folded around their adjacent corners against the side walls 3 and 3^A of the base and cover portions, which are now formed into these parts of the box. These ends 11 and 12 of the finished paper blanks are also made enough wider than the height of the end and side walls of the base and cover portions of the box to allow these ends 11 and 12 to project above the end and side walls of these members of the box, and these end portions are folded over the now formed end and side walls of the box into its interior, and are pressed against the interior surfaces of their walls, and being covered with gum they are glued to the interior walls of these members of the box, see Figs. 10 and 11. The side 13 of each finished paper blank is then folded up and pressed against the adjacent side 3, of the cover and of the base,

and over the end wrappings 11 and 12, which have been previously glued to these parts, and these side flaps 18 being also gummed, are glued to the adjacent side 3, 5 of both the cover and base portions of the box, and these sides 18 of the finishing blanks are also made enough wider than the height of the side walls 3 of these members to permit them to be folded over the upper 10 edge 5 of each, and are pressed down into the inside surface of the sides 3, to dotted line 11^A, and like end flap 14^A, see Figs. 10 and 11.

Having now framed up the pairs of pasteboard blanks and their pairs of finishing 15 covering blanks, into permanent base and cover portions of the box with straight right angled walls, and glued the sides 18 of the flaps to one side of these base and cover portions they will appear as shown in Figs. 10 20 and 11, in which it will be noticed that the opposite sides 13^A and 14^A of the finished paper blank have not been applied to the base or the cover, as they still remain flat, as illustrated, but can if desired be turned 25 up and be pasted against the base or cover, which will only leave the end portions standing vertically, as illustrated in Fig. 16. We will, however, leave them flat until we have inserted the body portion 5 in the base. 30 Consequently the next step in my method of box construction is to insert the ring shaped body portion 5 in the base member of the box. To accomplish this action, the base is held in position to receive this body portion 35 5, and the body portion is moved over and down into it, against its floor, and it can be secured to the base by any suitable means against accidental displacement therefrom. I preferably glue it sufficiently to cause it to 40 stick to the interior walls of the base. This body portion is made wide enough so that when it is inserted in the base, it will project far enough above the base to form a rim for the cover to fit over, and it also 45 forms a depth of body in the box equal to the combined height of the interiors of the base and cap, or nearly so, for the reception of cigarettes or other articles.

Having now completed the base and cover 50 to that point where they are ready to be assembled together, I will now describe this step in my method of constructing boxes. The boxes are then positioned to receive the covers and the covers are positioned to be 55 quickly and accurately placed over the upwardly projecting portion of the body portion of the base. This operation can be done by hand or other suitable means. The cover is then moved onto the upper rim portion 60 of the body and against the upper edges of the base, and its sides and ends are held to fit evenly flush with the sides and ends of the base. The next step is to fold or move either the side flap 13^A or 14^A against the 65 cover and base, and we will for the sake of

clearness move the flap 14^A down against the side of the cover and across the joint between the cover and base and against the adjacent side of the base, and as it is covered with gum it is glued securely to and over the entire surface of the side and base from the edge of the cap to the bottom edge of the base and forms the pivotal hinge of the cover on the base, and the cover can be lifted and will swing open on this paper hinge member up from and clear of the ring shaped body of the box, as shown in dotted lines, Fig. 15. The hinged covered box is now completed and ready to be turned over to the manufacturer to be filled with cigarettes or with any other articles or commodities for which it is adapted, and the manufacturer after filling the box, say with cigarettes, wets the extension flap 18^A of the base and folds and presses the flap against the side of the base across the joint between the base and the cover and entirely over the side of the cover to its top edge, and seals the cover to the base and across the joint between the two, and completes the box, as shown in Fig. 17.

From the above it will be seen that these finished paper blanks are especially made of unequal length, so that they will wrap from say the top edge of the cover down over one side of the cover and the adjacent side of the base to its lower edge, and from the lower edge of the base up against its side and over the cover to its top edge, or vice versa as the case may be. Consequently both sides of the box are completely covered by the flaps 13^A and 14^A of the finishing paper blanks, which are especially cut to cover the opposite sides of the completed assembled box, and they add additional strength to the 100 box, as well as giving to the box the appearance of being wrapped with a wrapping that extends continuously around the box, as the ends of these longer side flaps are 105 preferably arranged to coincide exactly the edges of the base and cover of the box, where the joint is not nearly as noticeable as if it occurred along the width of the sides.

While I preferably extend the extra length flaps to the opposite corners of the cap and base, my object is accomplished just the same if these flaps extend from either the cap or base entirely over the joint between these two parts of the assembled box. Consequently it is not essential that they extend entirely to the edges of these parts, it being sufficient if they extend from one over onto the other.

I have particularly described the longer flaps 14^A as being particularly moved against the side of the cover and base to form the hinge, and the flap 13^A on the base as being reserved or retained to seal the cover to the base on the opposite side of the cover from its hinge, for the sake of clearness in follow-

ing the different actions in assembling and completing the box. As a matter of fact, however, it is immaterial whether the longest flap of the cover or that one on the base, 5 is used for the hinge, as each extends to the opposite corner edge of the other, and either can be used for the hinge member, in which case the remaining one would be reserved for sealing the cover to the base. In the 10 mechanism employed for pressing a flap for the hinge, however, one of these will be used consecutively for the hinge and the other left consecutively for the sealing strip, as the bases and covers are fed in successive 15 order through the machinery.

In Fig. 16, I illustrate a slight modification in the arrangement of the finishing paper blanks and their arrangement to form the hinge member for the cover and 20 the sealing strip to seal the cover to the base. In this modification, one finishing blank is made to cover the ends and sides of the cover completely and to lap over onto the inside of the sides and ends of the cover, and the 25 other finishing blank is made to cover the ends of the base and also the opposite sides of the base, and these side flaps of the base are also made long enough to extend far enough beyond the ends of the base to lap 30 across the joint between the cover and base and lap over onto the cover, see Fig. 16, so that one of said flaps of said base is adapted to be glued to said cap and form a hinge member that will hinge the cover to the base, 35 and the other flap of the base on the opposite side of the base from the hinge member is adapted to be adhesively pressed against and secured to the cover in such a way as to seal the cover to the base, which of course 40 would not be done until the assembled box with its cover hinged to it, had been filled with cigarettes or some other commodity. These finished paper blanks can be provided with such printed matter, pictures, and artistically arranged decorative matter as is 45 desired, to make the boxes attractive.

My invention contemplates boxes made without the interior body portion, and also contemplates the making of boxes of hexagonal and other polygonal forms and shapes.

My new method of making paper boxes provides a strong, neat, hinged, covered box that can be constructed at much less expense than the hinged boxes at present in use; and while I have illustrated and described the preferred method of constructing and assembling the various elements of

my invention, I do not wish to be limited to those illustrated and described, as many changes may be made without departing from the spirit of my invention.

Having described my invention, what I claim as new and desire to secure by Letters Patent, is:

1. A box, having base and cover members, a finishing-sheet for each of said members, said finishing-sheets having elongated flaps forming cover-hinging and sealing members.

2. A box, having base and cover members, a finishing cover-sheet for each of said members, said finishing cover-sheets having flap members of such length that the flap forms a hinge on one side of the box between the cover and base, and the other flap forms a seal on the other side of the box.

3. A box, having base and cover members, a finishing cover-sheet for each of said members, each of said finishing cover-sheets having flaps, the flap of one of said sheets entirely covering one side of both base and cover members and acting as a hinge, and the flap of the other of said sheets acting as a seal for the base and cover members.

4. A box, having base and cover members, a finishing cover-sheet for each of said members, said finishing cover-sheets having integral flap members of such length that one flap forms a hinge on one side of the box between the cover and base, and the other flap forms a seal on the other side of the box.

5. In a box, body members comprising base and cover portions, a finishing-sheet covering each of said portions, each of said finishing-sheets having relatively shallow flaps covering the ends and one side of its respective body portion and a relatively deep flap which covers entirely one side of the box, one of said relatively deep flaps forming a hinge for the cover, and the other of said deep flaps forming a seal.

6. In a box, body members comprising base and cover portions, an upright collar within the box over which the cover fits, a finishing-sheet covering each of said body portions, each of said sheets having an elongated flap, one of said flaps providing a hinge for the cover and the other of said flaps forming a seal for the box.

In testimony whereof I affix my signature in presence of two witnesses.

PHILIP STANLEY SMITH.
